DISTRIBUTOR FOR PULVERIZED FUEL

Filed Dec. 26, 1929

FIG. 1.

FIG. 2.

FIG. 3.

INVENTOR

Harold E. Yarrow,

BY

James L. Morris

ATTORNEY

UNITED STATES PATENT OFFICE

HAROLD EDGAR YARROW, OF SCOTSTOUN, SCOTLAND

DISTRIBUTOR FOR PULVERIZED FUEL

Application filed December 26, 1929, Serial No. 416,619, and in Great Britain November 13, 1929.

The object of this invention is to provide means whereby pulverized fuel from a single pulverizer and its conveying or primary air may be distributed substantially equally between two or more discharge points.

According to this invention the pulverized fuel and conveying air are discharged downwardly through a conveying trunk or pipe upon a substantially horizontal plate or disc contained in a closed casing and having preferably a concave surface, over the edges of which the fuel spills evenly and thence passes inwardly between deflecting vanes into a whirling chamber leading to a receiving chamber having a plurality of equal and equally spaced discharge outlets. The result of the gyratory movement imparted to the fuel mixture by the inclined or curved deflecting vanes is that the mixture is distributed evenly around the inside of the receiving chamber and each of the outlets gets an equal supply of fuel.

One embodiment of the invention is illustrated in the accompanying drawings, where in Fig. 1 is a vertical section of a multiple distributor, and Figs. 2 and 3 are transverse sections on lines 2—2 and 3—3 respectively of Fig. 1.

In these drawings A is the air trunk or pipe into which the pulverized fuel and its conveying air are delivered at considerable velocity from the pulverizer or by means of a primary air fan from a store of already pulverized fuel, and from which it passes to the multiple distributor which consists of a cylindrical casing H having access hand-holes spaced around its periphery.

Inside the cylinder is a conical whirling chamber D formed of a ring of inclined deflecting blades or vanes C which rest on an internal flange at the bottom of the cylindrical casing H and have their upper ends fixed to a steel saucer-shaped plate B.

Below the whirling chamber D is a receiving chamber F which may be in the form of an inverted cone and which has equally spaced around it a plurality of identical discharge outlets G, which may be provided with suitable valves to close down or regulate the fuel mixture issuing from them.

The quantity of fuel passing through the distributor may be regulated by means of an annular diaphragm E provided with operating rods extending through the top of the distributor, whereby it can be moved upwards or downwards.

Having thus described the nature of the invention and the best means I know of carrying the same into practical effect, I claim:—

1. A distributor for pulverized fuel, comprising a whirling chamber into which the mixture of pulverized fuel and its conveying air is discharged, means for distributing the fuel substantially uniformly around the outer region of the whirling chamber, fixed deflecting vanes separating the outer from the inner region of the whirling chamber, a receiving chamber located below and communicating with the inner region of the whirling chamber and provided with a plurality of equally spaced discharge outlets. 60 65 70

2. A distributor for pulverized fuel comprising a whirling chamber, means for delivering fuel in a substantially even stream to said whirling chamber, said whirling chamber being provided with a substantially horizontal deflector plate upon which the fuel mixture is discharged and over the edge of which it falls in a substantially even stream around the outer region of the whirling chamber, and the said deflector plate being provided with deflecting vanes between which the fuel stream passes into the interior of the whirling chamber, and a receiving chamber located below and communicating with said whirling chamber. 75 80 85

3. A distributor for pulverized fuel according to claim 2, wherein the substantially horizontal deflector plate is concave or cupped on its upper side. 90

In testimony whereof I have signed my name to this specification.

HAROLD E. YARROW.
